Brown & Hall

UNITED STATES PATENT OFFICE.

GEORGE VAN WAGENEN, OF NEW YORK, N. Y.

STOVE.

SPECIFICATION forming part of Letters Patent No. 372,831, dated November 8, 1887.

Application filed March 4, 1887. Serial No. 230,153. (No model.)

To all whom it may concern:

Be it known that I, GEORGE VAN WAGENEN, of the city and county of New York, in the State of New York, have invented a new and useful 5 Improvement in Stoves, of which the following is a specification.

My invention more particularly relates to stoves which may be employed in heating cars or boats, and which are so constructed as to 10 prevent the escape from confinement of the fire in case the stove shall by any accident be overturned or injured.

In my application for Letters Patent, Serial No. 228,015, filed February 18, 1887, I have 15 shown a stove formed of two or more shells or casings surrounding one another and separated by air-spaces, which are bridged over by braces or pins in order to hold the shells or casings at the requisite distance apart in case of accident. That stove has at the top a smoke-outlet, which is formed by coincident openings in the several shells or casings, each protected by a guard consisting of parallel bars arranged in close proximity to each other, so as to form 20 narrow spaces between them, and I have also shown a cleaner or scraper, which, by reciprocating movement transversely to the length of the bars, serves to keep clear the spaces between them.

Important objects of my present invention 30 are to provide for more readily and thoroughly cleaning a grating composed of parallel bars, and also to give the pins or studs which constitute braces supporting the shells 35 or casings, and which are fixed in one shell or casing, a broader and more stable bearing upon the other shell or casing, so that the studs or braces will not be liable to be bent over laterally in case the stove is subjected to 40 a crushing blow or force, but will maintain their normal position at right angles to the shells or casings between which they extend.

In carrying out my invention I construct 45 the scraper or cleaner, whereby the guards of the smoke-outlet are kept clean, with teeth or projections to enter between the bars forming the guards, and adapting the scraper or cleaner to be slid lengthwise of the bars. I also construct the braces which bridge over the air-spaces between the two shells or casings in the 50 form of posts or studs, which are secured each

in one shell or casing, and have a broad end or foot for bearing against the adjacent shell or casing.

In the accompanying drawings, Figure 1 is 55 a sectional elevation of the upper portion of a stove, which is very similar to that forming the subject of my aforesaid application and in which my present invention is embodied. Fig. 2 is a transverse section of one of the series of 60 bars which guard the smoke-outlet, also showing the cleaner or scraper having teeth or projections for entering between these bars, and which is designed to be reciprocated lengthwise of the bars; and Fig. 3 is a horizontal 65 section of a portion of the concentric shells forming the stove-body and illustrating my improved braces or posts bridging over the spaces between these shells or casings, the said figure being upon a larger scale than Figs. 1 70 and 2.

Similar letters of reference designate corresponding parts in the several figures.

In this example of my invention the stove is formed by shells or casings $A A' A^2$, which 75 surround one another, and are closed by top plates, $B B' B^2$. The inner shell or casing, A , which constitutes the fire-pot, may be of cast or wrought iron or steel, and I prefer to make the outer shells or casings, $A' A^2$, of steel or 80 iron plate. The casings or cylindric shells $A A' A^2$ and their several top plates, $B B' B^2$, are maintained at a fixed distance apart, in order to form air-spaces $b b'$ between said shells or casings and between their plates $B B' B^2$. 85 I have represented the several shells or casings as maintained at proper distances apart by posts or braces C , which, as here represented, are secured by riveting or otherwise at one end, c , in the shell or casing, and have 90 at the other end each a broad foot or end portion, c' , which has a broad bearing upon the adjacent shell or casing. When the braces or posts C are thus constructed, each with a broad foot or end for bearing on the shell or casing 95 adjacent to that in which a post or brace is secured, there is no liability of the post or braces being upset or bent over laterally in case of the stove being subjected to a crushing force or blow, as there would be if the 100 posts or braces were of the same small diameter to their bearing ends and were destitute

of the broad end portions or feet, c' , just described.

In each of the top plates, B B' B², I have represented a smoke outlet or hole, d , and these several plates are connected by thimbles or flanged distance-pieces D, whereby they are connected at proper distances apart and whereby the smoke-outlet d in each plate is surrounded. The lower flange of each distance-piece D may be secured by riveting, as at d' , to one of the top plates, and the upper flange of such distance-piece may be detachably secured to another of said top plates by bolts d^2 , or otherwise. The smoke-outlet, 15 which is formed by the coincident openings d in the several top plates, terminates in a nipple or projection, D', adapted to receive a smoke-pipe, and each of the openings d is guarded or protected by a grating composed 20 of parallel bars d^3 , arranged in close proximity to each other and forming spaces between them. I have shown, for keeping clear each guard, a scraper or cleaner, d^4 , which may be operated by a handle, d^5 , and which has its 25 edge serrated or provided with teeth or projections, as shown in Fig. 2, to enter the spaces between the bars d^3 and keep them clear of ashes and soot. The scraper or cleaner d^4 , when constructed with teeth or projections, as 30 described, is to be reciprocated or slid lengthwise of the bars d^3 , in order to keep clear the spaces between them.

To prevent the escape of small pieces of coal or hot ashes in case of the stove being overturned, I arrange within the stove, and at a 35 little distance below the top plate B, in which is the first outlet-hole d , a shield or plate, E, which is imperforate and larger in horizontal area than the smoke-outlet d . The shield or 40 plate E is at a little distance below the smoke-outlet, and prevents small scraps of red-hot coal or ashes from escaping through the smoke-

outlet in case of the stove being overturned. The plate E is hung upon studs e , provided at the ends with heads and very loosely-fitting 45 holes $e' e'$, formed in the shield or plate E and in the top plate B. The large heads of these pins or studs e hold the plate or shield E in the position shown in Fig. 1; but they fit so loosely in their holes $e' e'$ that in case of the 50 stove being overturned the shield or plate E will by gravity be caused to close tightly down upon the smoke-outlet d , and absolutely prevent the escape through the gratings d^3 of any particles of red-hot coal or ashes.

I only seek to cover herein a brace or stud, C, broadened at one end, the other end being secured to the shell or jacket; and I do not claim herein a brace or stud broadened as well at the end which is secured to the shell or 60 jacket as at the free end, because such a claim is included in my application Serial No. 231,382, filed March 18, 1887.

What I claim as my invention, and desire to secure by Letters Patent, is—

1. The combination, with the stove-top having its smoke-outlet protected by a guard composed of parallel bars, of a scraper or cleaner having teeth or projections which enter between the bars and adapted to be reciprocated 70 over the guard in a direction lengthwise of the bars, substantially as herein described.

2. The combination, in a stove, of two or more shells or casings, one surrounding another and forming air-spaces between them, and braces bridging over such air-spaces, and each consisting of posts or studs secured in one shell or casing, and having a broad end or foot for bearing against the adjacent shell or casing, substantially as herein described.

GEO. VAN WAGENEN.
